UNITED STATES PATENT OFFICE

2,635,850

FLATWORK FEEDER TRUCK

James G. Mulvihill, Chicago, Ill., assignor to
 David A. Freeman Corporation, Chicago, Ill., a
 corporation of Illinois

Application September 30, 1948, Serial No. 52,081

4 Claims. (Cl. 254—2)

1

This invention relates to trucks or carts and, more particularly, to a feeder truck for use in a commercial laundry and the like for handling a large volume of damp clothes during the cleaning operation.

Heretofore, in handling the damp clothes from the washer to the drying or pressing machine, the clothes were taken from the washer, placed on a truck or cart, transported to the dryer or presser, and there manually lifted from the truck and fed into the adjacent machine. This operation, particularly the manually lifting of the damp clothes from the truck, was a laborious as well as time-consuming task. The task became increasingly more difficult the damper the clothes were when removed from the washer.

It is one of the objects of this invention to provide a feeder truck which will greatly facilitate the removal of the wet clothes from said truck regardless of their dampness.

It is a further object of this invention to provide a feeder truck which will expedite the handling of damp clothes so as to increase the efficiency and reduce the cost of the cleaning operation.

It is still a further object of this invention to provide a feeder truck which is of simple, yet sturdy construction, effective in operation, and inexpensive to produce.

Further and additional objects will appear from the description, accompanying drawings, and appended claims.

In accordance with one embodiment of this invention, a feeder truck is provided comprising a movable frame having a pair of rotatably mounted, elongated reels disposed at either side of said frame, a flexible container suspended from said reels and having the sides thereof windably mounted thereon, and means for controlling the rotation of said reels. The controlling means are regulated by the operator of the truck so that the bottom of the flexible container may be raised as the damp clothes are removed therefrom and fed into the pressing or drying machine, thus eliminating the need for the operator to bend over and lift out the clothes from the bottom of the container.

For a more complete understanding of this invention, reference should now be had to the drawings wherein—

Fig. 1 is a fragmentary top plan view of the feeder truck.

Fig. 2 is a fragmentary side elevational view of the feeder truck showing the bottom of the container in its lowered position ready to receive the damp clothes from the washer.

Fig. 3 is a fragmentary end view of the feeder truck showing the manually operable controls for raising the floor of the container; and

Fig. 4 is a fragmentary end view of the truck showing a modified form of manually operable controls for raising the floor of the container.

Referring now to the drawings, a feeder truck

2

10 is provided for use primarily in a commercial laundry for transporting bundles of damp clothes from the washer to the drying or pressing machine, comprising a frame 12, a pair of elongated reels 14 and 16 rotatably mounted on said frame, and an expansible and contractible container 18 suspended from said reels within said frame.

The frame 12, in this instance, is of a rectangular parallelepiped design having a base 20, to the underside of which, at the four corners thereof, are rotatably mounted rollers or casters 22, and vertically extending end plates or partitions 24 and 26 disposed in spaced substantially parallel relation at the narrow ends of the base and adapted to form two sides of the container 18.

Rotatably mounted on the upper end of plates or partitions 24 and 26 and arranged along either side of the frame are reels 14 and 16. The reels extend from one plate to the other and are adapted to act to a certain extent as a spacer for said plates. Secured to either end of the reels 14 and 16 and disposed on the outside of end plates 24 and 26 are sprocket gears 28 and 30 respectively which cooperate with other controls, to be hereinafter described, to cause said reels to be rotated in opposite directions.

Container or web 18, which is constructed of some durable fabric, rubberized, or plastic material, is suspended from reels 14 and 16 as above mentioned. The sides 32 and 34 of the container are windably mounted on reels 14 and 16 respectively and, upon rotation of the reels, the bottom 36 thereof is raised or lowered. The container 18 is substantially the same length as the space between the end plates. Resting on the bottom 36 of the container is a bottom element or floorboard 38 which retains the sides 32 and 34 in a substantially vertical position while being wound or unwound from the reels. The board is substantially the same length and width as the container, and is constructed of some lightweight stiff material such as wood.

For regulating the rotation of reels 14 and 16, two forms of controls are shown in Figs. 3 and 4. In Fig. 3, which is the preferred form, sprocket gear 30 which is keyed to reel 16 meshes with a pinion gear 40 and a gear 42. Gear 42 is rotatably mounted on end plate 26 and on its shaft 50 44 is keyed a second gear 46 intermediate gear 42 and the outside surface of plate 26. Cooperating with gear 46 is a chain 48 which also engages and drives sprocket gear 28 keyed to reel 14. Pinion gear 40 is rotatably mounted on end plate 26 and meshes with gear 30 and drives the same. Mounted on the shaft 50 of pinion gear 40 is a handle 52 which extends outwardly from plate or partition 26 and is adapted to be gripped by the operator. Upon rotation of handle 52 in a clockwise direction, sides 32 and 34 of the container are wound on reels 14 and 16 respectively and the bottom 36 of the container is raised. A pawl 53 pivotally mounted on plate

or partition 26 releasably engages with the teeth of gear 40 and prevents lowering of the bottom of the container once it has been raised to the desired height by the operator. A like arrangement of the operating controls is found on plate 24 of the frame, so as to enable the container to be adjusted from either end of the frame.

In the modified form for controlling the rotation of the reels, as shown in Fig. 4, a shaft 54 is rotatably mounted on end plate or partition 26 and arranged transversely relative to axes of reels 14 and 16. Worms 56 and 58 formed on shaft 54 engage with gears 28 and 30 respectively, mounted on reels 14 and 16, and rotate said reels in opposite directions relative to one another. At one end 62 of the shaft is mounted a handle 62 which may be removed therefrom and mounted on the other end 64 of the shaft so as to make the controls more accessible to the operator. Like controls are also mounted on end plate 24.

Thus it will be seen that a feeder truck has been provided for use in a commercial laundry and the like which will greatly facilitate the handling of damp clothes regardless of their dampness during the cleaning operation so as to increase the efficiency and reduce the cost of such an operation.

While several embodiments of this invention are shown above, it will be understood that the invention is not to be limited thereto, since many modifications may be made, and it is contemplated, therefore, by the appended claims to cover any such modifications as fall within the true spirit and scope of this invention.

I claim:

1. A variable capacity carrier comprising a mobile supporting frame, a horizontally disposed vertically movable non-deformable bottom element, a pliable web mounted on and suspended within said frame and having vertically disposed side-forming portions windably mounted on said frame and a center portion interconnecting said side-forming portions for supporting and subtending said bottom element, said web cooperating with said supporting frame and bottom element to form a box-like container having an open top, and means mounted on said frame and operatively connected to said web for simultaneously effecting winding or unwinding of said side-forming web portions to vary the volumetric capacity of said box-like container.

2. A variable capacity carrier comprising an upright supporting frame having spaced upright substantially parallel end partitions and a pair of spaced substantially parallel horizontally disposed reels rotatably mounted on and interconnecting the upper edge of said end partitions, a vertically movable horizontally disposed non-deformable bottom element having a width and length corresponding substantially to, respectively, the spacing between said end partitions and the spacing between said reels, a pliable web disposed intermediate said end partitions and said reels, said web having side-forming portions windably mounted on said reels and a center portion interconnecting said side-forming portions and supporting and subtending said bottom element, said web having a width corresponding substantially to the spacing between said end partitions and cooperating with said end partitions, bottom element, and reels to form a box-like container having an open top, and means mounted on one of said end partitions and operatively connected to both of said reels for simultaneously effecting winding or unwinding of the side-forming por-

tions of said web to vary the volumetric capacity of said box-like container.

3. A device of the class described comprising an upright supporting frame having spaced upright substantially parallel end partitions, a pair of spaced substantially parallel reels rotatably mounted on said end partitions and extending transversely therefrom, a pliable web having a width substantially the same as the length of said reels and having the opposite edges of said web windable on said reels, a non-deformable height-adjustable bottom element disposed intermediate said reels supported and subtended by said web and having a length substantially the same as the spacing between said end partitions and a width substantially the same as the spacing between said reels, and means for simultaneously controlling the rotation of said reels; said means comprising gears mounted on the corresponding ends of said reels, a manually operated drive gear rotatably mounted on one of said end partitions and in meshing relationship with one of said reel gears, a gear rotatably mounted on said one end partition and in meshing relationship with said one reel gear, and means for imparting the rotational movement of said gear mounted on said one end partition to said other reel gear whereby said reels rotate in opposite directions and at the same speed.

4. A device of the class described comprising an upright supporting frame having spaced substantially parallel end partitions, a pair of spaced substantially parallel elongated reels disposed transversely relative to said end partitions, each of said reels being rotatably supported at opposite ends by said end partitions, a continuous pliable web suspended from said reels, a non-deformable bottom element disposed intermediate said reels supported and subtended by said web, said web, frame, and bottom element coacting with one another to form a box-like container having substantially vertical sides, a substantially horizontal bottom and an open top, and means mounted on said frame for effecting winding and unwinding of the vertical sides of said container on said reels to vary the volumetric capacity of said container; said means comprising gears mounted on the corresponding ends of said reels, a manually rotatable drive gear rotatably mounted on one of said end partitions, and being meshable with one of said reel gears, a pair of coaxially arranged gears rotatably mounted on said frame and having one of said gears meshable with said one reel gear and the other gear being operatively connected to the other reel gear whereby said reels will rotate simultaneously in opposite directions and at the same speed upon rotation of said drive gear.

JAMES G. MULVIHILL.
